UNITED STATES PATENT OFFICE.

FOSTER J. HULL, OF HAGERSTOWN, MARYLAND, ASSIGNOR TO THOMAS W. PANGBORN COMPANY, OF HAGERSTOWN, MARYLAND, A CORPORATION OF NEW YORK.

SAND-BLAST APPARATUS.

1,196,362.

Specification of Letters Patent. Patented Aug. 29, 1916.

Application filed October 7, 1912. Serial No. 724,292.

To all whom it may concern:

Be it known that I, FOSTER J. HULL, a citizen of the United States, and a resident of Hagerstown, county of Washington, and 5 State of Maryland, have invented certain new and useful Improvements in Sand-Blast Apparatus, of which the following is a specification.

My invention relates to improvements in 10 sand blast apparatus, and particularly to improvements in what are known as sand blast barrels.

Sand blast barrels are commonly used for 15 cleaning small castings, and other small objects, and comprise a rotary barrel, drum or container, into which a charge of the castings or other objects to be cleaned is introduced, and then the barrel is caused to rotate, and at the same time sand blast apparatus is operated, the blast or blasts being 20 caused to impinge upon the castings, etc., in the barrel.

My invention consists in the novel mounting 25 or support of the blast nozzles, in the novel means employed for supplying abrasive material to such nozzles, in the novel arrangements for charging the barrel, in the novel arrangements for discharging the contents of the barrel, in the novel means provided for delivering sand continuously from 30 the barrel to the sand hopper in the normal operation of the machine, and in other features hereinafter described and particularly pointed out in the appended claims.

The objects of my invention are to 35 combine high efficiency of blasting operation with ease of handling and facility in receiving and discharging castings and other objects to be acted upon; to make the apparatus self-contained, dispensing with accessory apparatus, other than the necessary exhaust connection for removing dust; to so 40 design the machine that it may be set on any kind of floor without excavation and without foundation, and without extensions below 45 the floor line, such as sand pits, elevators, settling chambers, etc.; to so construct the machine that the blasts shall spread with approximate uniformity over the entire charge 50 of the drum, and shall reach objects which lie at the ends of such drum equally as well as those near the center of the drum, to cause the blasts to act sidewise on the articles to be cleaned, as well as radially, so that edges, 55 recesses, sides, etc., of the castings or other

objects shall be exposed to the action of the blasts; to render the direction of action of the blasts adjustable during the operation of the machine; to render the sand hopper of the machine accessible at all times, and to render the sand feed visible so that it is easy to determine by visual inspection that all of the blasts are operating properly; to provide for ready cleaning of the sand inlet, while the machine is in operation, in case 60 such sand inlet should become obstructed; to provide for the ready charging and discharging of the drum; to make the apparatus automatic in action, simple, durable, efficient and compact; to so design the apparatus that relatively small power shall be required for its operation; to adequately protect the gears, bearings, etc., from dust and wear, and to provide for the ready replacing of such parts of the machine as are 65 necessarily exposed to the abrasive action of the blast.

Other objects of my invention will appear hereafter.

I will now proceed to describe my invention with reference to the accompanying drawings, and will then point out the novel features in claims.

In said drawings: Figure 1 shows a front view of the machine, the charging door of the case inclosing the drum being shown in open position. Fig. 2 shows a rear elevation of the machine. Fig. 3 shows a detail side elevation of the sand blast manifold and Fig. 4 shows an end view of such manifold. Fig. 5 shows a detail transverse section of the sand feed box. Fig. 6 shows an elevation of the left hand side of the machine, and Fig. 7 shows an elevation of the right hand side of the machine. Fig. 8 shows a transverse section of the machine. Fig. 9 shows a vertical section of the machine, the section being taken through the axis of rotation of the drum. Fig. 10 is a fragmentary detail sectional view of the locking mechanism for the door of the drum. Fig. 11 is a fragmentary longitudinal section of the blast nozzle manifold.

The improved sand blast machine herein illustrated comprises a drum consisting of 105 side plates 1 (Fig. 9) provided on their peripheries with gear teeth 2 (Figs. 1 and 9) and a screen cylinder 3 the ends of such screen cylinder 3 fitting within annular shoulders 4 provided on the inner faces of 110

these side plates 1. The side plates are held together by through-bolts 5 and are spaced apart by spacing sleeves 6 surrounding said through-bolts. The screen cylinder 3 is provided with a swinging charging door 7 (see particularly Fig. 8), hinged to the screen cylinder and provided with suitable locking means hereinafter described. The side plates 1 of the drum are provided with suitable journals 8 located within bearings 9 of an outer case, such case comprising a lower section 10 of substantial construction adapting it to support the drum and its load, and an upper section 11 of lighter construction. This upper section 11 of the outer case is provided on the front side of the machine with a door 12 adapted to swing about an axis substantially coincident with the axis of rotation of the drum. This door is supported by radius arms 13 secured to bearing rings 14 rotatably mounted upon the external cylindrical surfaces of the bearings 9 of the drum. Within the lower section 10 of the outer case of the machine, there is an inclined shelf 15 having in it a discharging opening 16; and a swinging shelf 17 is provided, which shelf in one position closes this opening 16, forming with shelf 15 an inclined surface down which sand from the drum may slide to a suitable screen 18 and thence to the sand hopper 19; while in its other position (the position shown in full lines in Fig. 8) the swinging shelf 17 forms a shelf down which the charge of the drum may slide when the door of the drum is opened for discharging. The front of the lower section 10 of the inclosing case is substantially open from the bottom up to the upper end of the inclined shelf 15, so that a car may be run directly into this inclosing case to receive the charge of the machine when the latter is discharged from the drum and slides down shelf 17. A transverse support 20 is provided for supporting the swinging shelf 17 in its lowermost position; that is to say, the position it occupies when the charge of the drum is being discharged. A transverse brace 21 is provided for the lower section 10 of the outer case of the machine, but this transverse brace 21 has a large central aperture 22, so that access is easily obtained to the space behind it and sand or other objects which may find their way into such space are easily removed. Another transverse brace 23 is provided at the front, but this brace is also provided with a large central aperture 24 through which a tool may be introduced if necessary to assist in the descent of the castings, etc., along the shelf 17.

The swinging door or shelf 17 is mounted upon a hollow shaft 25 having suitable bearings in the sides of the lower section 10 of the machine, and said shaft is provided at

one end with a lever 26 by which the swinging door 17 may be operated, and is also provided with a weight 27, which crosses the perpendicular when the door 17 is moved from one position to the other, so that said weight 27 causes the door to remain in the one position or the other, unless positively moved. The weight of castings or the like dropping upon the door 17 when the drum is opened will be sufficient, ordinarily, however, to cause the door 17 to swing automatically to the position shown in Fig. 8.

The door 17, and the sides of the shelf 15, extend right to the surface of the shaft 25; the screen 18 also extends right to that shaft; and so does the inclined shelf 28, forming the bottom of the sand hopper 19. When the door 17 is in its closed position, therefore, sand escaping from the screen cylinder 3, is caused to pass through the screen 18 and into the sand hopper 19, without opportunity to escape elsewhere.

The drum 1—3, is rotated by means of a shaft 29 (Figs. 8 and 9) provided with pinions 30 engaging the gear teeth 2 of side plates 1; said shaft 29 being driven by suitable reduction gearing 31—32 from a shaft 33 upon which are tight and loose belt pulleys 34 and 35. The shaft 33 extends through the machine and is provided on its opposite side with a wheel 36 which forms convenient means for turning over the drum by hand when this is desirable, and may be used as a brake drum if desired.

Within the blast drum is mounted a blast manifold 37 shown particularly in Figs. 3, 4, 8 and 9. This manifold is provided with journals 38, the bearings for which are formed by the end plates 39 of the bearings for the drum itself. Dust-tight packing 40 is provided to prevent sand from reaching these journals and bearings, and a lever 41 is provided, by which the manifold may be adjusted in position angularly. To hold the manifold in any position to which it may be adjusted, this lever 41 is provided with a spring actuated latch dog 42 engaging teeth 43 (Fig. 7) on the periphery of one of the bearing end plates 39. The manifold is provided internally with ducts 44, 45, 46 and 47, which ducts terminate, beyond the ends of the manifold, in fittings 48 adapted to receive flexible hose. Duct 44 is a live air duct for the supply of air or other blast fluid, under pressure, to the blast nozzles, herein-after mentioned, carried by the manifold. Ducts 45, 46 and 47 are suction ducts, connected by hose 45^a, 46^a and 47^a to sand feed boxes 49 at the rear of the machine and communicating with the sand hopper 19. One of these feed boxes is shown in section in Fig. 5.

50, 51 designate sand blast nozzles carried by the manifold 37. In the construction shown the manifold is provided with three

of these nozzles and therefore there are three suction ducts, 45, 46 and 47, provided in the manifold. Of course the number of nozzles may be greater or less, in which case the number of suction ducts in the manifold will be correspondingly greater or less. In the particular construction of nozzles shown in Figs. 8 and 11, each nozzle is provided with a removable nozzle tip 51 held in place within the nozzle by a screw bushing 52. Each nozzle is connected, by a flexible tube 53, with the live air duct 44. Each nozzle comprises a suction chamber 54 to which is connected the corresponding suction duct, 45, or 46, or 47, as the case may be. It will be seen that when air under pressure is discharged through live air duct 44, and the induction nozzle 55 (Fig. 8) forming the blast nozzle termination of that live air duct, suction is produced in chamber 54, which suction draws a mixture of sand and air from the corresponding feed box 49 up through the corresponding hose 45^a, or 46^a, or 47^a, and the corresponding suction duct 45, or 46, or 47 of the manifold, the sand so drawn into the blast nozzle 50 mixing within that nozzle with the live air discharged through nozzle 55, and thence being projected with great force from the blast nozzle 50 against the contents of the drum.

In the arrangement of nozzles on the manifold shown particularly in Fig. 9 (which arrangement has been found to be especially advantageous) only the center nozzle is positioned approximately radially; the other two nozzles are positioned obliquely so as to direct their blasts, the one toward one end of the drum, the other toward the other end of the drum. The angular positions of the two outer nozzles 50 are such with reference to the length of the drum and with reference to the angle of dispersion of the jets, from these nozzles, that the entire length of the drum is swept by the jets with substantial uniformity. The angular projection of the jets from the two side nozzles 50 is of great advantage as thereby the jets from these nozzles are able to clean sides and edges of the objects treated, and to penetrate into side recesses of such objects, as they could not if the jets were projected substantially radially.

As shown particularly in Fig. 5, each sand feed box 49 is provided with a port 56 communicating with the interior of the sand hopper 19. Each box is further provided with a suction pipe 57 having an inlet port 58, which pipe 57 projects out beyond the side of the box 49 and has connected to it an appropriate suction tube 45^a, or 46^a, or 47^a, as the case may be. Each of these boxes 49 is further provided with a baffle 59, the position of the bottom of which is such as to prevent choking of the supply port 58 of the feed pipe 57. It has been found that, except

for this baffle 59, there is a tendency, during periods of idleness of the machine, for the sand to bank up in the feed boxes 49, so as to completely close the openings 58; and when this occurs, since entrance of air through these ports 58 is cut off, the feed is choked. But by the provision of the baffle 59, the sand in the immediate vicinity of the ports 58 cannot rise so as to completely close said ports 58, however the sand may bank up behind the baffle 59. Between the lower edge of the baffle 59 and the ports 58 the sand cannot exceed its natural angle of repose. The pipes 57 are rotatable for adjustment of the position of the ports 58 with reference to the lower edges of the baffles 59, and therefore the rate of feed of the sand. The feed boxes 49 are customarily provided with swinging covers 60 which, when opened, permit visual inspection of the feed of the sand to each nozzle. It is therefore easy to determine while the machine is running, whether all of the nozzles are operating or not. In case any nozzle fails to operate, such failure will be due to clogging of the port 58 from one cause or another, and it is easy to introduce a tool and clear this port 58 from any obstruction without interfering with the operation of the machine. A door 61 on the rear side of the sand hopper 19, permits inspection of such hopper when desired, and visual observation of the height and condition of sand therein. In the rear side of the outer case of the machine there is also provided an exhaust connection 62 to which may be connected a suitable exhaust fan, for the removal of dust.

The latch mechanism for holding the charging door 7 of the blast drum 1-3 closed, is shown particularly in Figs. 1, 8 and 10, and comprises a latch lever 63 pivoted at 64 to the door 7 and connected, on opposite sides of its pivot, to sliding spring-actuated bolts 65 adapted to engage suitable locking recesses 66 provided on the inner surfaces of the side plates 1 of the blast drum. When the door is closed the bolts 65 engage the outer surface of the drum and hold the door closed. The pivot for the door 7 is at 67 (Fig. 8).

The operation of the machine is as follows: In charging the machine the swinging door 12 of the outer case is raised, the blast drum 1-3 turned around until its door 7 is opposite the opening left by the raising of the door 12, and then the door 7 is opened and latched in open position, and the charge of castings or other objects to be sand blasted is introduced into the drum. The doors 7 and 12 are then closed, the rotation of the drum started, and air or other blast fluid under pressure admitted to duct 44. In practice the drum 1-3 is rotated about three revolutions per minute, in the direction of arrow shown in Fig. 8. The

articles to be sand blasted therefore occupy approximately the position indicated in dotted lines in Fig. 8. The diameter of the drum 1-3 and the position of the blast 5 nozzles 50 within that drum is so regulated in the design of the machine, that the surface of the pile of material to be blasted is about six inches from the orifices of the blast nozzles, it having been 10 learned by actual experience that this is the most efficient distance of the nozzles from the work, using the ordinary abrasive materials and ordinary blast pressures. As the drum rotates the material within it is 15 tumbled about, new surfaces being constantly exposed to the action of the blasts. When the sand blasting has been continued for a sufficient length of time, the supply of air under pressure to duct 44 is discontinued, so stopping the sand blasting. The 20 cover 12 is raised, and, when the door 7 comes opposite the opening provided by the raising of said cover, said door 7 is opened and latched in open position, and the drum 25 rotated until the doorway in said drum is opposite the opening 16 in inclined shelf 15. The contents of the drum are then dumped automatically from the drum, and, if the swinging shelf 17 has not already been lowered to the position shown in Fig. 8, the 30 weight of the objects upon it will move it to that position, whereupon the charge of the drum will slide down this swinging shelf 17 to the floor, or upon a car which may 35 have been run in underneath this shelf 17 to receive the charge. A new charge may then be introduced into the drum and the door 7 and the shelf 17 returned to their closed positions and the rotation of the drum resumed. Then upon turning on the supply 40 of live air to duct 44 a suction is immediately produced in chamber 54 and communicated through the flexible hose 45, 46^a and 47^a which automatically re-starts the flow 45 of sand from sand boxes 49.

While in Fig. 8 I have indicated a position assumed by the charge of the machine during the rotation of the drum, it will be obvious that this angular position of the 50 surface of the charge with respect to the horizontal will vary with varying speeds of the drum and with varying nature of the contents of the charge. Round castings (shot for example) would assume only a 55 relatively small angle; while spiders and other objects with projections may naturally assume quite an oblique angle. In order that, notwithstanding this variation in angle of the surface of the charge, the 60 blast may be projected as directly as possible against the charge, the manifold 37 is made rotatable as shown, and may be adjusted through a wide angle, while the machine is in operation. Another advantage 65 of the rotatability of the manifold is that

this rotatability makes it easy to move the manifold into position opposite the door 7, when the nozzle tips must be removed or the air connections renewed.

It will be observed that in this machine 70 the sand flow is automatic; there is no sand valve to manipulate. Sand starts to flow when the air is turned on, and stops flowing when the air is turned off. There being a "sight feed" to each blast nozzle, if any nozzle fails to operate, for any reason, that fact may be readily determined by inspection of the corresponding feed box.

I am aware that heretofore sand blast barrels have been employed wherein blasts are 80 introduced from opposite ends of the barrel. When this is done, the blast jets must travel a considerable distance before they encounter the main portion of the charge in the barrel, and it is well known that the 85 efficiency of the blast decreases greatly with increase in distance. Furthermore, the two blasts introduced from opposite ends of the drum have a tendency to neutralize each other. To obviate these objections, sand 90 blast barrels have been built in which the entire sand blast mechanism is located within the barrel, a plurality of nozzles being provided which project the sand-blasts normally against the surface of the charge. 95 The location of the sand blast mechanism within the barrel itself is extremely objectionable, and the normal arrangement of the nozzles does not provide efficient distribution of the jets. By the arrangement of 100 nozzles shown herein, I attain substantially uniform distribution of the jets over the surface of the charge without interference between several jets. The door 7 being hinged near the top of the charging and discharging opening in the drum, and being arranged to swing inwardly, is out of the way, in its inward position, both when the drum is being charged and when the drum is being discharged, and does not conflict or 105 interfere with the covering over of the drum by the curved cover 11 and door 12 which are separated from the drum by a few inches only. In addition, the door 7, when at its inner position, and when the drum is being discharged, forms an abutment to prevent the objects within the drum from falling across the discharging opening in the drum, to the opposite side of such opening and beyond, instead of passing out through such opening, as they should.

Since the swinging door 12 of the case is substantially concentric with the drum, and swings upward and backward, no additional head room is required to permit the raising of said door 12, such as would be required if the door were a vertically sliding door, and no additional space in front of the machine is required, as would be the case if the said door swung outwardly.

What I claim is:—

1. Sand blast apparatus such as described, comprising a rotary screen drum, a blast nozzle therein, and a case inclosing said drum and having, beneath the drum, a sand receptacle, said case having an opening, opposite the side of the drum and located, in greater part, above the axis of the drum, and having a door for such opening where-
15 by access may be obtained to the drum, said drum having in its side, and adapted to register with the opening of the case, a charging opening, and having also a door, for closing such charging opening, arranged to swing in-
15 wardly and upwardly within the drum when the opening of said drum is in registry with the opening of said case; said case provided with a sloping shelf beneath the drum, ar-
15 ranged to permit sand falling thereon from the drum to slide by gravity into said sand receptacle.
2. Sand blast apparatus such as described, comprising a rotary screen drum, and a case inclosing said drum and having, beneath
25 the drum, a sand receptacle, said case having an opening, opposite the side of the drum, through which the drum may be charged, said drum having in its side, and adapted to register with the opening of the
30 case, a charging opening, and having also a door for closing such charging opening, said door pivoted near that edge of said charging opening of the drum which is the upper edge when the said charging opening
35 of the drum is in registry with the opening of the case, and arranged to swing inwardly and upwardly within the drum; said case provided with means beneath the drum ar-
40 ranged to permit sand falling from the drum to slide by gravity into said sand receptacle.
3. Sand blast apparatus such as described, comprising a rotary screen drum, and a blast nozzle therein, said drum having in its
45 side an inwardly swinging charging door, bearing therefor and a case inclosing said drum the top of which case is cylindrical and comprises an upwardly and rearwardly swinging charging door whereby access may
50 be obtained to the drum, and bearings for said door, mounted upon and arranged to turn about the bearings for said drum.
4. Sand blast apparatus such as described, comprising a rotary screen drum, and a case
55 inclosing said drum, a sand receptacle, said case having an opening, opposite the side of the drum, through which the drum may be charged, said drum having in its side, and adapted to register with the opening of
60 the case, a charging opening, and having also a door for closing such charging open-
65 ing, said door pivoted near that edge of said charging opening of the drum which is the upper edge when the said charging opening
66 of the drum is in registry with the opening
- of the case, and arranged to swing inwardly and upwardly within the drum, and latching mechanism for the door of the drum adapted to hold the door in either its closed or its open position; said case provided with means beneath the drum arranged to permit sand falling from the drum to slide by gravity into said sand receptacle. 70
5. Sand blast apparatus such as described, comprising in combination a rotary screen 75 drum, a blast nozzle therein, a support for said drum comprising a casing inclosing the drum and having an inclined shelf adapted to receive sand escaping from the drum, said shelf having an opening through which the 80 contents of said drum may be discharged, and a swinging shelf arranged in one position to close such opening in the inclined shelf, and in another position to form a slide down which the material discharged from 85 the drum may pass; said drum provided with a discharge door. 85
6. Sand blast apparatus such as described, comprising in combination a rotary screen 90 drum, a blast nozzle therein, a casing inclos- 95 ing said drum and provided beneath the drum with a sand hopper, said casing having beneath the drum a screen forming the top of such sand hopper, and having also an inclined shelf adapted to receive sand escaping from the drum, such shelf having in it an opening for the escape of material discharged from such drum, and a swinging shelf which in one position closes such opening and in another position forms a slide 100 down which the material discharged from the drum may pass; said drum provided with a discharge door. 100
7. Sand blast apparatus such as described, comprising in combination a rotary screen 105 drum, a blast nozzle therein, a support for said drum comprising a casing inclosing the drum and having an inclined shelf adapted to receive sand escaping from the drum, said shelf having an opening through 110 which the contents of said drum may be discharged, and a swinging shelf arranged in one position to close such opening in the inclined shelf, and in another position to form a slide down which the material discharged 115 from the drum may pass; said drum pro- 120 vided with a discharge door; and a support against which such swinging shelf rests when material discharged from the drum is passing over it. 120
8. Sand blast apparatus such as described, comprising in combination a rotary screen 125 drum, a blast nozzle therein, a support for said drum, comprising a casing inclosing the drum and having an inclined shelf, adapted to receive sand escaping from the drum, said shelf having an opening through which the contents of said drum may be discharged, and a swinging shelf arranged in one position to close such opening in the inclined 130

shelf, and in another position to form a slide down which the material discharged from the drum may pass; said drum provided with a discharge door, and means tending to hold said swinging shelf in either of such two positions.

9. Sand blast apparatus such as described, comprising in combination a rotary screen drum, a blast nozzle therein, a support for 10 said drum comprising a casing inclosing the drum and having an inclined shelf adapted to receive sand escaping from the drum, said shelf having an opening through which the contents of said drum may be discharged, 15 and a swinging shelf arranged in one position to close such opening in the inclined shelf, and in another position to form a slide down which the material discharged from the drum may pass; said drum provided 20 with a discharge door, said case being open in the line of discharge of material down such swinging shelf.

10. Sand blast apparatus comprising in combination a rotary drum, and a blast 25 manifold therein provided with a plurality of blast nozzles, said manifold having a plurality of sand supply ducts, one for each such nozzle, and having also means, other than said sand supply ducts, for supplying 30 blast fluid under pressure to said nozzles.

11. Sand blast apparatus comprising in combination a rotary drum, a blast manifold therein provided with a plurality of blast nozzles, said manifold having a plurality of sand supply ducts, one for each 35 such nozzle, and means for supplying blast fluid under pressure to said nozzles, said manifold being rotatable, whereby the angle of projection of the blasts may be varied.

40 12. Sand blast apparatus comprising in combination a rotary drum, a sand blast manifold therein provided with a plurality of nozzles arranged to project their blasts divergently with respect to one another, said 45 manifold being rotatable, and being provided with means for supplying of sand and air to said nozzles.

13. Sand blast apparatus comprising in

combination a rotary drum having hollow supporting journals, bearings for said journals provided with end plates, and a blast nozzle support within said drum having bearings in the said end plates.

14. Sand blast apparatus comprising in combination a rotary drum having hollow 50 supporting journals, bearings for said journals provided with end plates, a blast nozzle support within said drum having bearings in the said end plates, and means for preventing sand from reaching said bearings. 55

15. Sand blast apparatus comprising in combination a rotary drum having journals, one of which is hollow, and a blast nozzle support within said drum and rotatably mounted within one of said journals. 60

16. Sand blast apparatus comprising in combination a rotary drum having journals, one of which is hollow, a blast nozzle support within said drum and rotatably mounted within one of said journals, said support 70 provided at its end with air and sand connections.

17. Sand blast apparatus comprising in combination a rotary drum having journals, one of which is hollow, a blast nozzle support within said drum and rotatably mounted within one of said journals, and means 75 for adjusting the angular position of said support.

18. Sand blast apparatus comprising in 80 combination a rotary drum having hollow journals, a blast nozzle manifold within said drum and rotatably mounted within said hollow journal, said journals being open at the ends, said manifold provided with a plurality of blast nozzles and with ducts for the supply of sand and blast fluid under pressure to said nozzles, said ducts terminating at the ends of said manifold. 85

In testimony whereof I have signed this 90 specification in the presence of two subscribing witnesses.

FOSTER J. HULL.
